(57) **CLAIM**

I claim the ornamental design for a fishing line spooler, as shown and described.

DESCRIPTION

FIG. 1 is a Perspective view of a fishing line spooler showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the fishing line spooler that form no part of the claimed design.
